[57] CLAIM

The ornamental design for a table for handicapped access, as shown and described.

DESCRIPTION

FIG. 1 is a front perspective view of the table for handicapped access showing my new design;

FIG. 2 is a front elevational view of the table for handicapped access thereof with the rear view being a mirror image;

FIG. 3 is a left side elevational view of the table for handicapped access thereof with the right side view being a mirror image;

FIG. 4 is a top plan view of the table for handicapped access thereof; and,

FIG. 5 is a bottom plan view of the table for handicapped access thereof.

FIGS. 2 through 5 have been shown on an enlarged scale.
